US00D977948S

(12) **United States Design Patent** (10) **Patent No.:** **US D977,948 S**
Graykowski et al. (45) **Date of Patent:** **** Feb. 14, 2023**

(54) **CARABINER**(71) Applicant: **Milwaukee Electric Tool Corporation**,
Brookfield, WI (US)(72) Inventors: **Anthony S. Graykowski**, Belgium, WI
(US); **Andrew G. Wagner**, Lisbon, WI
(US); **Derek Rose**, Menomonee Falls,
WI (US)(73) Assignee: **Milwaukee Electric Tool Corporation**,
Brookfield, WI (US)(**) Term: **15 Years**(21) Appl. No.: **29/826,608**(22) Filed: **Feb. 14, 2022****Related U.S. Application Data**(62) Division of application No. 29/727,535, filed on Mar.
11, 2020, now Pat. No. Des. 946,382, which is a
division of application No. 29/685,903, filed on Apr.
1, 2019, now Pat. No. Des. 882,378, which is a
division of application No. 29/634,242, filed on Jan.
19, 2018, now Pat. No. Des. 848,823.(51) **LOC (14) Cl.** **09-06**(52) **U.S. Cl.**USPC ..... **D8/356**(58) **Field of Classification Search**USPC D8/356, 354, 105, 349, 367; D3/207;

CLAIMWe claim the ornamental design for a carabiner, as shown
and described.**DESCRIPTION**FIG. 1 is a perspective view of a carabiner according to an
embodiment of the invention;

FIG. 2 is a right side view of the carabiner of FIG. 1;

FIG. 3 is a left side view of the carabiner of FIG. 1;

FIG. 4 is a back side view of the carabiner of FIG. 1;

FIG. 5 is a front side view of the carabiner of FIG. 1;

FIG. 6 is a top side view of the carabiner of FIG. 1; and,

FIG. 7 is a bottom side view of the carabiner of FIG. 1.
